BRICK KILN ARCH AND MEANS FOR AND
METHOD OF PRODUCING SAMEAdolph C. Lutter, Glenview, Ill., assignor to
Lutter Brick Company, Glenview, Ill., a corpora-
tion of Illinois

Application November 17, 1933, Serial No. 698,449

10 Claims. (Cl. 25—132)

The present invention relates to arch structures in brick kilns and means for producing the same.

Among the objects of the invention is to pro-
5 duce a novel arch structure between spaced
brick piles, wherein the arch forming bricks are
part of a pile and extend from it across the
arch space to another pile, thus providing a
space between the piles and beneath the extend-
10 ing bricks.

Brick arches have been formed or produced
by displacing bricks from the upper portions of
15 spaced companion piles of bricks to extend from
both piles into the space therebetween, and fill-
ing in the spaces behind the displaced bricks
with other or spare bricks usually placed on the
tops of the piles when they are formed, trans-
ferred, or set down. That entails considerable
20 hand labor and consumes time.

In the present invention, each pile is built up
on a suitable support, such as a car, in such a
way that the arch forming bricks are part of
the pile and are so arranged that when the pile
25 as a whole or as a unit is transferred and set
down in properly spaced relation with a pre-
viously set-down like pile, the arch forming
bricks extend across the space between the piles
and simply connect or match with the previous-
30 ly set down pile without any displacement of any
bricks or hand labor of any kind.

The support, as the car, preferably has means
located at a side of the car and the pile being
built-up on it, comprising at its upper end later-
35 ally extending or over-hanging supporting parts
or shoulders so constructed and arranged that
the position of the arch forming bricks will be
determined thereby and be held in proper rela-
tion with the remainder of the bricks of the
40 pile so that the pile including the arch forming
bricks may be lifted as a unit from the car and
said means, and be transferred and set-down as
explained above.

Another object of the invention is to provide
45 a novel process or method of forming brick arches
or arched brick kilns by so piling the bricks
of a pile in a generally rectangular pile that the
arch forming bricks extend from a side, such
as the upper portion of a side of the pile, and
50 so setting down the pile as a whole or unit in
spaced relation with a previously set down like
pile, that the arch forming bricks extend across
or span the upper portion of the space between
the piles, certain of the arch forming bricks,
55 such as the upper ones thereof, contacting with
or being partially supported by bricks of the up-

per portion of the near side of the previously
set down pile, so that a fire space is formed or
provided beneath the arch and between the piles.

Another object of the invention is to provide
5 a novel means for carrying out the herein dis-
closed novel process and for producing and
forming the novel brick arch.

Other objects, advantages, capabilities, fea-
10 tures and process steps are comprehended by
the invention as will later appear and as are
inherently possessed thereby.

Referring to the drawing;

Fig. 1 is a view in elevation of a pile of bricks
produced in accordance with the invention and
15 a view in section of a means for producing the
same; and,

Fig. 2 is a view in elevation of set down piles
and the arch therebetween.

Referring more in detail to the drawing, the
invention is shown in connection with a sup-
porting means, such as a car having a support-
ing platform 1 having supports 2 provided with
bearings 3 for shafts 4 to which are secured
wheels 5 operative over rails 6. Upon the plat-
form 1 are provided a number of longitudinally
20 disposed supporting elements 7 which may be
of channel iron.

At one side of the car, is secured a gauging
wall 8 against which the bricks may be placed
when being piled. The lower end of the wall 8
stands on the platform 1 and the upper end of
the wall 8 is provided a series of steps or later-
ally projecting portions 11, 12, 13 and 14 re-
spectively comprising supporting shoulders 15,
16, 17 and 18, as shown in Fig. 1 of the drawing.
Suitable brace members 19 may be secured at
30 their upper ends to the shoulder part 14 by
means of bolts 20, and near their lower ends to
the lower part of wall 8 by the rivets or bolts 9.
The lower ends of the braces 19 fit into stake
straps 10 which are secured by rivets or bolts
35 to a flange of the support 1, as shown in Fig. 1.
At the ends of the car are provided any suitable
number of posts or stakes 21 suitably secured
or fastened at their lower ends to the ends of
the platform 1. In order to assist the bracing
40 action of the braces 19, the latter are secured in
any suitable manner to a strap 22 having ends
23 extending to the ends of the car and secured
in any suitable manner to the stakes 21 as clear-
ly shown in Fig. 1.

The pile of bricks is built up on the car and
against the gauge wall 8 and the stepped up end
portion thereof by first placing the bricks 24 and
55 25 in line transversely of the car, these bricks

being placed edge on edge and forming the lower two courses of the pile. Each line of bricks 24 and 25 is spaced from the others so as to provide alternate spaces for the entry of forks of a Penfield transferring device in a manner well known in this art.

10 The third course of bricks 26 is arranged longitudinally of the car and crosswise of the lines of bricks 24 and 25, these bricks 26 being arranged in groups of three. The next course of bricks 27 is transverse of the car with the bricks arranged in groups of three bricks upon three bricks of the course 26. The next course 28 is piled exactly the same as course 26.

15 The next course 29 is piled the same as course 27 with the exception that bricks 30 are placed so as to be properly positioned by step 11 and partly supported on shoulder 15, and bricks 31 are placed behind bricks 30 as shown.

20 In the next course 32 the bricks are arranged as in courses 28 and 26 with exception that bricks 33 extend laterally or transversely and are properly positioned by step 12 and partly supported upon the shoulder 16.

25 The next course 34 is arranged as courses 29 and 27 with exception that bricks 35 are placed to be properly positioned by step 13 and partly supported upon the shoulder 17.

30 The next course 36 which is the upper course, has its bricks arranged as in courses 32, 28 and 26 with the exception that bricks 37 are so placed as to be properly positioned by the step 14 and partly supported upon the shoulder 18. The step 14 is wider than the other steps so that 35 the shoulder 18 may support about two thirds of the length of the bricks 37.

35 In this way it will be apparent that the bricks 30, 33, 35 and 37 extend laterally from the side of the pile yet are a part of the pile and also 40 constitute the arch forming bricks when the pile is set down in proper spaced relation with a previously set down like pile. It will also be noted that at the other side of the pile, the upper course 36 is so laid as to omit a line of 45 bricks to provide a shoulder 38, for supporting the ends of the bricks 37 of the next pile when the arch forming bricks span the space between the two piles, and thus complete the arch, as clearly shown in Fig. 2 of the drawing.

50 The means used for transferring the pile as a whole or as a unit from the car to be set down in the kiln, is known as a Penfield fork. It comprises suspending links 40 and 41 connected to cross arms 42 from an end of which 55 are suspending links 43 connected at their lower ends to a fork 44 having fingers or tines which are adapted to extend into the spaces provided between the rows of bricks 24 and 25. The fork is held in stable position by connecting members 45 secured to the fork at the lower ends 60 thereof and to the cross arms 42 at the upper ends thereof.

65 In the present invention, the Penfield device carries an additional means comprising rods 46 having secured at their outer ends 47 thereof, an angle iron 48 adapted to be positioned at the ends of the bricks 37 so that the arch forming bricks may be held in position and not become loosened or fall during the transferring of the 70 pile. The rods 46 extend back and have slotted bearings 49 in which fit pins 50 secured to the members 45, and the rods 46 may have rearwardly extending arms 51 having manual members 52. At the forward ends of the cross arms 75 42, are also connected hooks 53 for supporting

the rods 46 when the Penfield device is being moved to be applied to a pile of bricks on a car. The rods 46 also carry weight bars 55 and 56 extending longitudinally of the pile and having base flanges 57 and 58 to span over and press down on some of the bricks 36 and the bricks 37 so as to prevent the over-hanging bricks from dipping or the like when the pile is being transferred.

80 After the bricks are piled in the manner above described, the Penfield device together with the rods 46, weight bars 55 and 56 and the angle iron 48 in the position shown in Fig. 1, it is lifted by a suitable crane so as to carry the pile of bricks from the car, and then the Penfield device is lowered in the kiln so as to set down the pile of bricks on the floor or ground of the kiln. As the pile is lowered in place it is brought into proper spaced relation with a previously set down pile, a part of which is shown in the right hand side of Fig. 2, so that the outer end portions of the bricks 37 will fit into and be supported upon the shoulder 38 of the previously set down pile, thus connecting the arch forming bricks with that side of the previously set down pile as clearly shown in Fig. 2 of the drawing. As the pile is set down, the angle iron 48 which acts as a lateral support for the bricks 37, contacts with the bricks 54 of the previously set down pile so as to cause the member 48 to rise 30 out of engagement with the ends of the bricks 37, and also cause a raising of rods 46 and the weight bars 54 and 55, as shown in Fig. 2. After the pile is set down the operator may press down on the handle 52 and raise the rods 46 to engage 35 in the hooks 53. The Penfield device then is moved to the left so as to become disengaged from the pile and the crane will transfer it to the car for engagement of the forks with another pile on the car.

40 From the above, it will become apparent that an arched kiln is built without the displacement of any bricks from set down piles to form an arch. The arch forming bricks are made part of a pile and the whole pile as a unit together 45 with the arch forming bricks, is set down so that the arch forming bricks will match with or connect up with the previously set down pile in a substantially automatic manner. As shown in Fig. 2, a firing space 55 is provided for between the piles and beneath the overhanging or laterally extending arch forming bricks.

50 The width of the arch may be as desired. If it be desired to make it narrower than that shown on the drawing, the bricks 37 may jut 55 out only half as much as shown, as by omitting the bricks 36a behind the bricks 37. On the other hand, the arch width may also be made narrower by having less overhanging bricks, namely only bricks 33, 35 and 37, bricks 30 being so piled as not to jut.

55 While I have herein disclosed an embodiment 60 illustrative of the invention and a mode of producing the same together with an illustrative means of carrying out the process, it is to be 65 understood that the invention is not limited thereto but may comprehend other constructions, arrangements of parts, details, features and process steps without departing from the spirit of the invention.

70 Having thus disclosed the invention, I claim:

75 1. A brick arch structure formed between spaced piles of bricks, comprising bricks of one pile extending from a side thereof and into the space provided between the piles and with cer-

tain of said extending bricks being partly supported by bricks forming a portion of the side of the other pile of bricks at the other side of said space.

5 2. A brick arch structure formed between spaced piles of bricks, comprising bricks of one pile extending from a side thereof and into the space provided between the piles and with the upper bricks of said extending bricks being partly supported by bricks forming a portion of the side of the other pile of bricks at the other side of said space.

10 3. An arch structure for bricks in a brick kiln, comprising overhanging bricks from a side of a pile of bricks, the upper bricks of the overhanging bricks extending to and being partly supported by bricks in the upper portion of the near side of another pile of bricks spaced from the first mentioned pile of bricks, whereby a space is provided between said piles of bricks and beneath said overhanging bricks.

15 4. An arch structure for bricks in a brick kiln, comprising overhanging bricks from a side of a pile of bricks and so arranged that the upper bricks of the overhanging bricks are partly supported by and partly overlie bricks forming a part of the near side of another pile of bricks spaced from the first mentioned pile of bricks, whereby a space is provided between said piles of bricks and beneath said overhanging bricks.

20 5. An arch structure for bricks in a brick kiln, comprising overhanging bricks from a side of a pile of bricks and so arranged that the upper bricks of the overhanging bricks partly overlie and are partly supported by bricks in the upper portion of the near side of another pile of bricks spaced from the first mentioned pile of bricks, whereby a space is provided between said piles of bricks and beneath said overhanging bricks.

25 6. A pile of bricks of generally rectangular shape and having at an upper portion of a side thereof, outwardly projecting bricks to form an arch between said pile and a companion and like

30 pile in spaced relation thereto, and at the upper portion of the opposite side thereof having a shoulder for the partial support of certain of the projecting bricks of a companion and like pile in spaced relation thereto, whereby arched spaces are provided for between said piles.

35 7. A device for forming a pile of bricks for brick kilns, comprising a support on which the bricks are piled longitudinally and transversely in alternate layers in general, a member having laterally disposed supporting shoulders and being so located and arranged in respect to the pile of bricks to support some of the bricks of the pile in laterally extending relation to the side of the pile.

40 8. A process of forming arches in a brick kiln, comprising the steps of piling arch forming bricks with other bricks of a pile to form a generally rectangular pile with the arch forming bricks extending laterally from a side of the pile, and so setting down the pile in spaced relation with a previously set down like pile that the arch forming bricks extend across the upper portion of the space between the piles and form an arch therebetween.

45 9. A process of forming arched brick kilns, comprising piling bricks into a generally rectangular pile with arch forming bricks extending laterally from the upper portion of a side of the pile, and setting down said pile in spaced relation with a previously set down like pile with the arch forming bricks extending across the upper portion of the space between said piles and with certain of said arch forming bricks in engagement with bricks in the upper portion of the near side of the previously set down pile.

50 10. A brick arch structure formed between spaced piles of bricks, comprising bricks of one pile extending from a side thereof into the space provided between the piles and with certain of said extending bricks being in contact with an upper portion of the side of the other pile of bricks at the other side of said space.

ADOLPH C. LUTTER. 45
